Geo. P. Kimmel.

ATTORNEY.

UNITED STATES PATENT OFFICE.

GEORGE E. PULLIAM, OF MOUNT VERNON, ILLINOIS.

HURDLE AND VAULTING STANDARD.

1,388,821.

Specification of Letters Patent. Patented Aug. 23, 1921.

Application filed August 3, 1920. Serial No. 401,053.

To all whom it may concern:

Be it known that I, GEORGE ELMER PULLIAM, a citizen of the United States, residing at Mount Vernon, in the county of Jefferson 5 and State of Illinois, have invented certain new and useful Improvements in a Hurdle and Vaulting Standard, of which the following is a specification.

This invention relates to a combined vaulting and high jumping standard of the adjustable type.

The object of the invention is to provide a standard of this character which may be quickly and easily adjusted to support the 15 cross bar at different heights; the construction of which is cheap, and in which the jumping rope or cross bar may be conveniently replaced after it has once been dislocated.

Another object is to provide a standard of 20 this character equipped with a combined bar support and gage for jumping and light exercises.

With these and other objects in view, the 25 invention consists in certain novel features of construction as hereinafter shown and described and then specifically pointed out in the claims, and in the drawings illustrative of the preferred embodiment of the 30 invention.

In the accompanying drawing:

Figure 1 represents a front elevation with parts broken out of a standard constructed in accordance with this invention.

Fig. 2 is a similar view taken from the 35 opposite face of the standard.

Fig. 3 is a side elevation thereof, and,

Fig. 4 is a transverse section taken on the line 4—4 of Fig. 1.

Fig. 5 is a detail side elevation of the 40 sliding member.

In the embodiment illustrated a supporting base 1 is shown which is constructed of two members 2 and 3 composed of two 45 wooden pieces 4" by 4" by 16" with square notches as 4 cut in their opposed faces midway their ends so that the pieces will be held in operative position. While the base is preferably constructed as above described it 50 need not necessarily be so formed.

Rising from this base 1 is a standard 5 composed of telescopically engaged sections 6 and 7 the section 6 being fixed at one end to the base 1 and hollow throughout its 55 length to receive section 7. The interior of this section 6 is preferably angular in cross

section and the section 7 is correspondingly shaped to fit and slide therein. The base is preferably constructed of heavy material while the standard sections are made of 60 light timber preferably of cypress or red wood. As shown the hollow section 6 is composed of two flat face members 8 and 9 with side strips 10 arranged between them at their side edges to form spacers and thus 65 provide the hollow interior thereof to receive the sliding section 7. The outer faces of the face members 8 and 9 are divided into inches, feet, and fractions of an inch, one side being intended for use for measuring 70 vaulting heights while the other side is designed for use in high jumping. Arranged in each of these face members 8 and 9 are a plurality of longitudinally spaced alined sockets 11 which are designed to receive a 75 pin presently to be described.

The sliding inner section 7 has a flexible element 12 secured to one end therof a staple 13 being preferably provided for this purpose. This element or cable 12 may be 80 composed of any suitable non-stretchable wear resisting material preferably of piano wire and it may be of any desired length, a pin 14 being carried by its free end and adapted to engage one of the apertures 11 85 in the standard section 6 for holding the sliding section 7 in adjusted position. This cable 12 lies in a groove formed in one face of member 7, (see Fig. 4) to permit said member 7 to slide freely in member 6 without binding. A laterally extending pin 15 projects from the upper end of the sliding section 7 and is designed to form a support for a cross bar when the standard is used for high jumping it being of course understood that two of these standards are used to support such a bar. This pin 15 may 90 serve as a rest for the cross bar or it may be inserted in a socket of the cross bar so as to permit said bar to be readily knocked down and yet held against accidental disengagement such as might occur by a gust of wind if it were not properly connected. 95

A roller or pulley 16 is mounted in the upper end of the standard section 6 and is 100 designed to receive the wire or cable 12 and to guide said cable when a pull is exerted thereon for raising and lowering section 7.

From the above description it will be obvious that when the standard is in the position shown in Fig. 1 and it is desired to 110 lengthen it the pin 14 is disengaged from

the socket 11 in which it is mounted and a pull exerted thereon which causes the section 7 to move upwardly in section 6. After this section has been raised to the desired extent the pin 14 is inserted in the socket opposite on the standard section 6 and thus section 7 will be held in adjusted position.

From the above description it will be obvious that a standard as herein shown and described will be simple and cheap to manufacture and yet may be easily and quickly adjusted to meet varying conditions.

The preferred embodiment of the invention is disclosed in the drawings and set forth in the specification, but it will be understood that any modifications within the scope of the claims may be made in the construction without departing from the principle of the invention or sacrificing any of its advantages.

What I claim is:

1. In a standard of the class described two telescopically engaged members, a pulley carried by the fixed member, and a flexible element secured to the inner end of the slidable member and passed over said pulley

to effect movement of said slidable member in one direction by a pull exerted on the free end of said element, a pin carried by said flexible element, and a plurality of longitudinally spaced sockets carried by the fixed member said pin being insertible in one of said sockets to hold the slidable member in adjusted position against the force of its weight.

2. A standard of the class described comprising a supporting base, a hollow fixed standard rising therefrom, a pulley mounted in the upper end of said standard and the opposed faces of said standard provided with a plurality of sockets, an extension member mounted to slide in said hollow standard and having a flexible element secured to the lower end thereof and passed up over said pulley, one of said members having a groove to receive said element and permit the free movement of the slidable member, the slidable member being provided with cross bar supporting means.

In testimony whereof, I affix my signature hereto.

GEORGE E. PULLIAM.
